CLAIM

The ornamental design for a combined bite block and cusps, as shown and described.

DESCRIPTION

FIG. 1 is a front elevational view of a combined bite block and cusps showing my new design;

FIG. 2 is a top plan view of a combined bite block and cusps shown in FIG. 1. The bottom plan view is identical;

FIG. 3 is a side elevational view of the combined bite block and from the right-hand side of FIG. 1. The left-hand side is a mirror image;

FIG. 4 is a rear elevational view of a combined bite block and cusps shown in FIGS. 1-3;

FIG. 5 is a cross-sectional view thereof, taken on the line 5—5 of FIG. 4; and,

FIG. 6 is an isometric view of a combined bite block and cusps shown in FIGS. 1-5.

FIG. 6.

FIG. 2.

FIG. 1.

FIG. 3.

FIG. 4.

FIG. 5.
